RALPH OLAF HELGEBY, OF FLINT, MICHIGAN, ASSIGNOR TO A C SPARK PLUG COMPANY, OF FLINT, MICHIGAN, A COMPANY OF MICHIGAN

RATCHET-DRIVE REDUCTION

Application filed June 2, 1928. Serial No. 282,423.

This invention relates to mechanism for driving one member from another at a reduced speed ratio. The invention has been designed more particularly for use where considerable reduction is required, as for example in the case of odometers. More particularly the invention makes use of a plurality of ratchet wheels and a single operating pawl.

10 The object of the invention is to secure reduction between a driving and driven member, the reducing means having maximum simplicity. To this end the invention aims to avoid the use of interengaging gears. As a 15 further object, the novel structure is designed to be quiet in operation and inexpensive in manufacture. Other objects and advantages will be apparent from a reading of the following description.

20 In the drawing, Figure 1 is a view of the improvement in elevation. Figure 2 is a transverse section. Figure 3 is a view in elevation of the pawl and ratchet. Figure 4 is a view also in elevation of a modified form of 25 ratchet wheel.

Referring by reference characters to the drawing, numeral 10 is a drive shaft rotatably mounted in a suitable frame 12. The shaft 10 is held in position by a clip 14 which is carried by frame 12 and which is received in a slot 16 of shaft 10, as shown in Figure 2.

On the end of shaft 10 is an eccentric 18 upon which is pivotally mounted pawl 20. A screw 22 or other suitable means is used to 35 secure the pawl in position on the eccentric. The pawl 20 is provided with an aperture 24, one wall of which is shaped as a cam, as shown in Figure 3, and this cam shaped wall is arranged to engage and to ride upon a pin 28 held by the frame 12. A spring 30 secured in position by fastening means 32 normally presses the pawl toward the pin 28 and the ratchet wheel with which it is to engage.

Numeral 34 represents a primary ratchet wheel idly rotatable on shaft 36 secured to the frame 12. The ratchet wheel 34 is pressed against a shoulder 38 of shaft 36 by a spider spring 40, the latter engaging the ratchet wheel 34 and in abutment with frame 12. By 50 this means sufficient friction is developed be-

tween the flange 38 and the wheel 34 to resist relative movement when the pawl is lifted from the ratchet wheel by engagement with the pin 28 and while it is being returned by the eccentric 18. Ratchet wheel 34 is provided with a number of shallow teeth 42 and at one or more predetermined intervals with deep teeth 44. It is obvious that a single deep tooth as in Figure 3 may be used, or that two or more such teeth 44 as suggested by Figure 4 may be used. If desired for any specific purpose the deep teeth may be arranged out of symmetry. They may be successive teeth if that arrangement be preferred.

There is a secondary ratchet wheel 46 adjacent to and coaxial with the first wheel 34, this second wheel being also rotatable on shaft 36. Ratchet wheel 46 is provided with teeth 42', in number the same as the teeth of ratchet wheel 34. The outside diameter of the ratchet wheel 46 is slightly less than that of wheel 34 measured at the bottom of the shallow teeth. As shown in Figures 1 and 2, ratchet wheel 46 carries a standard transfer disc 47 as is ordinarily used in odometers. Between disc 47 and the wheel 46 proper is a space 48 in which is received a bifurcated stamped ring 50. A star pinion shaft 52 provided with star pinions 56 for the successive rotation of figure wheels one of which is designated by numeral 54 may be used to hold the stamping 50 in position. Stamping 50 is formed with curved legs within space 48 to provide a resilient means whereby wheel 46 resiliently engages flange 38. The purpose of this frictional engagement is to retain ratchet wheel 46 in fixed position except when being driven by the pawl 20. This construction relative to the spring plate 50 is more fully described in my application Serial No. 251,145, for "ratchet driven odometer mechanism," and filed February 1, 1928.

The operation of the device as explained above may be briefly described.

The drive shaft 10 is driven in the direction indicated by the arrow in Figure 1 by any suitable driving means. This shaft as it rotates causes the oscillation of pawl 20. As the pawl moves backward away from the ratchet wheel, the cam surface 26 engages the pin 28

and causes the pawl to be lifted from the ratchet teeth, thereby avoiding wear and noise. On the forward movement the pawl will engage teeth 42 or 44. For each rotation of the shaft 10, the pawl will move ratchet wheel 34 one tooth, thereby reducing the motion of the drive shaft in proportion to the number of the teeth in ratchet wheel 34. As stated above there may be one or more deep teeth 44 according to the further reduction required. Each time the pawl enters a deep tooth 44 it engages one of the teeth 42 of the secondary ratchet wheel 46 and moves that wheel a distance of one tooth. Very great reduction is therefore easily effected without the use of gear teeth which would require relatively expensive gear cutting and accuracy in assembling to secure correct center distances.

20. The advantages may well be explained by a typical case. If a reduction from 1024 to 1 is desired, the ratchet wheels may each be given 32 teeth, 32 being the square root of 1024, and only one of the teeth of wheel 34 will be cut deep. When the drive shaft 10 has made 1024 revolutions, the primary wheel 34 will have completed 32 revolutions and, since there is but one deep tooth the second wheel 46 will have been given one complete rotation. If a reduction of 1024 to 2 be desired, two deep teeth will be provided on wheel 34 instead of one. It will be obvious that the deep teeth may be symmetrically arranged, or may be arranged as desired to secure a desired character of rotation of the second wheel 46. For example, the two deep teeth may be in sequence so that the second wheel will be moved by each of the two successive movements of the pawl and thereafter may remain at rest until the pair of deep teeth are again in position to be engaged by the pawl. It will also be seen that more than one wheel 34 may be used to secure even greater reduction. By the above constructions a very simple device has been arranged to secure very considerable reduction in drive ratio. This expedient is useful in many relations and particularly in drives for odometers. It avoids the expense of gear cutting and accuracy in assembling gear shafts.

50. I claim:

1. In drive reduction a plurality of adjacent coaxial ratchet wheels, one of said wheels being an idler, together with a driving pawl engaging the teeth of the idler, said idler having a deep tooth whereby the pawl may engage the teeth of the adjacent ratchet wheel.
2. The invention set forth in claim 1, together with pin means fixed in position, said pawl having a cam surface to engage said pin means whereby said pawl may be lifted from said ratchet wheel in its retrograde movement.
3. The invention defined in claim 1, together with a pin fixed in position and said

pawl having a recess with an internal cam edge to engage said pin whereby said pawl may be lifted in its retrograde movement.

4. In combination, a driven rotatable shaft having an eccentric pin, a spring pressed pawl pivoted on said pin, an idler ratchet wheel having a plurality of teeth to be engaged by said pawl, at least one of said teeth being relatively deep, an adjacent coaxial ratchet wheel of lesser diameter, the diameter of the second wheel being such that its teeth are engaged by said pawl when the pawl enters said deep tooth of the first ratchet wheel.

5. The invention defined by claim 4 together with cam means associated with said pawl whereby the pawl is automatically disengaged from the ratchet wheels on the retrograde movement thereof.

6. In drive reduction, a plurality of adjacent coaxial ratchet wheels, one of said wheels being an idler, together with a driving pawl, engaging the teeth of said idler, said idler having a plurality of deep teeth whereby the pawl may engage the teeth of the adjacent ratchet wheel.

In testimony whereof I affix my signature.

RALPH O. HELGEBY.
